Fig. 4.

Inventor:
Charles B. Arnold.
By *Wm. M. & Wm. M. Attey.*

UNITED STATES PATENT OFFICE.

CHARLES B. ARNOLD, OF CHICAGO, ILLINOIS, ASSIGNOR TO SEYMOUR & PECK CO., OF CHICAGO, ILLINOIS, A CORPORATION OF DELAWARE.

BARREL.

Application filed June 8, 1927. Serial No. 197,260.

This invention relates to a barrel or drum of the type which is made up of inner and outer veneer plies suitably reinforced exteriorly by a plurality of hoops.

5 For its principal objects my invention aims to provide a construction which will be tighter, stronger and more durable than what is now known. This is accomplished by the special arrangement and combination of the 10 several barrel components in a manner which is hereinafter set forth in detail.

A suggestive embodiment of my invention is illustrated in the accompanying drawings in the manner following:

15 In the drawings:

Figure 1 is a perspective view of the barrel in its entirety;

Fig. 2 is a central longitudinal section therethrough;

20 Fig. 3 is an enlarged fragmentary sectional view with certain of the parts broken away to exhibit other parts rearwardly thereof;

Fig. 4 is a plan or development view of 25 the shook from which the barrel is formed;

Fig. 5 is a longitudinal section therethrough taken on line 5—5 of Fig. 4; and

Fig. 6 is a fragmentary end elevation of 30 the barrel with a portion of the cover broken away to exhibit the construction rearwardly thereof.

The barrel comprises the usual cylindrical body A having reinforcing hoops B applied circumferentially to the exterior thereof.

35 The barrel ends are adapted to be closed by heads C secured in place as hereinafter explained.

Referring particularly to Fig. 3, I have shown the barrel body as formed of an outer 40 ply 7 of veneer having its grain running around the barrel. This outer ply may consist of one piece of veneer extending for the length of the barrel, or it may be of several pieces joined edge to edge as at 8. Associated with this ply is an inner ply of veneer 9 which preferably is in the form of staves. The grain of this inner ply runs lengthwise of the barrel, or counter to that of the outer 45 ply 7. Any suitable means of joining the inner and outer plies together may be used, an effective adhesive being suggested for this purpose. It may also be found desirable to apply to the inside face of the inner ply a lining 10 which extends for substantially the 50 entire length thereof. Such a lining may

conveniently be formed of paper having suitable properties to protect the contents of the barrel.

The hoops B which are applied exteriorly to the barrel may be secured thereto with the aid of nails or staples 11. Near the opposite ends of the barrel are inside stays in the form of hoops 12 and 13 spaced apart a suitable distance for the accommodation between them of heads C. The same fastening devices 11 for securing the hoops B may also connect the stays to the barrel, as indicated best in Fig. 3.

In the construction of the present barrel it may be desired to first produce a shook or mat such as is suggested in Fig. 4. This comprises the inner and outer plies arranged and united as already described, also the hoops which are applied thereto, all extended flat for convenience in handling and shipping. The opposite edges of the shook which are 75 joined to form the barrel body are preferably scarfed as at 15, as are also, at 16, the opposite ends of the several hoops. When formed into a cylinder, the scarfed ends of the body and hoops may overlap as indicated in Fig. 6, 80 without increasing the thickness of the barrel at this point of connection. In this operation the meeting ends of the shook may be connected by an adhesive, and also by nails or staples 17.

85 A construction answering to the preceding description will be found advantageous in numerous respects. The securement of the top barrel head C may be deferred until it is desired to seal up the contents of the barrel. At that time the head C which fits tightly against the inner ply of the barrel body is forced to a position of rest against the stay 12, following which the end stay 13 is secured in place. This movement of the barrel head to final position is ordinarily attended with considerable friction against the inner ply 9, the thickness of which is very slight. By extending the staves forming this ply clear to the end of the barrel and having the grain of the staves lengthwise thereof, the barrel head C may be driven, if necessary, to a position of rest without destroying or otherwise breaking down the barrel interior. This is a feature of great advantage which is not present in containers of the present day.

90 According to the present method of preparing shooks for barrels of two or more plies, a revolving drum is used as a form. Before the meeting edges of the shook can 100

be joined, it is necessary to trim them off. The product formed in this manner requires greater equipment and time than for the barrel of the present invention which may advantageously be produced otherwise. I prefer to prepare the shook on a flat table, binding its plies together by nails, staples, adhesive, or other fastening means, and then trimming off and scarfing its edges which are to be joined. The hoops also are secured to the shook, the ends thereof being accurately trimmed and scarfed in the manner hereinbefore described. No further operation on the shook is necessary other than rolling it into cylindrical form and joining its edges at the time that the barrel is to be set up. By proceeding in this manner I am enabled to produce a barrel of the kind described with greater expedition and accuracy.

20 I claim:

1. A barrel in which is comprised a cylindrical body of veneer plies, the outer ply having its grain running around the barrel and the inner ply having its grain disposed lengthwise of the barrel, both plies extending for the full length of the barrel, reinforcing hoops applied circumferentially to the ex-

terior of the barrel; a pair of stays in spaced relation adjacent each end of the barrel and applied interiorly thereof, and a head driven to place and extending across each end of the barrel and tightly fitting against the inner ply thereof, the head being confined in place between the associated pair of stays, substantially as described.

2. A barrel in which is comprised a cylindrical body formed of inner and outer plies of veneer, the former having its grain running lengthwise of the barrel and the latter having its grain running counter thereto, both plies terminating flush at opposite ends of the barrel, a reinforcing hoop applied exteriorly of the barrel adjacent one end thereof, a stay applied interiorly of the barrel slightly removed from said end thereof, a head for closing the barrel having its edges fitting tightly against the inner ply thereof and adapted to be driven to a final position against the stay, a second stay on the opposite head side adjacent the barrel end, and fastening means for securing the hoop and stays to the barrel, substantially as described.

CHARLES B. ARNOLD.
